UNITED STATES PATENT OFFICE.

HERBERT E. PENNEY, OF MINNEAPOLIS, MINNESOTA, ASSIGNOR TO W. S. NOTT COMPANY, OF MINNEAPOLIS, MINNESOTA, A CORPORATION.

STEAM-GENERATOR.

SPECIFICATION forming part of Letters Patent No. 717,914, dated January 6, 1903.

Application filed April 26, 1902. Serial No. 104,754. (No model.)

To all whom it may concern:

Be it known that I, HERBERT E. PENNEY, a citizen of the United States, residing at Minneapolis, county of Hennepin, and State of Minnesota, have invented certain new and useful Improvements in Steam-Generators, of which the following is a specification.

My invention relates to vertical steam-boilers in which both water-tubes and partially-submerged flues are employed; and its object is to improve the water circulation and increase the efficiency of the boiler as a rapid steam-generator.

My improvements are illustrated in the accompanying drawings, in which—

Figure 1 is a vertical sectional view of the boiler, and Fig. 2 is a horizontal sectional view on the line $z z$ of Fig. 1.

In the drawings, 1 designates the outer cylinder or shell of the boiler, and 2 a concentric inner cylinder or shell, preferably of approximately half the height of the outer shell, an annular space 3 being provided between the two shells to serve as a water-leg. The two shells are connected by stay-bolts 4 or equivalent devices for holding them in position against pressure in the intervening space, and the annular space 3 is closed at the bottom by a suitable ring 5. The inner shell is covered by a crown-sheet 6. A fire-grate 7 is suitably supported near the bottom of the inner shell, and a fire-door 8 is provided near the base of the shells to give access to the combustion-chamber. In the latter chamber are water-tubes arranged in series in parallel vertical planes, the tubes of each series or section inclining in opposite direction from those of the adjoining sections. These tube-sections are each composed of vertical headers 9, arranged at opposite sides of the chamber, and inclined tubes 10 in staggering order connecting the headers.

The tube-sections are connected to the water-leg 3 by means of pipe-couplings 11, screwed into the lower ends of the headers, and hollow plugs 12, adapted to screw into sockets in the elbows 13 of the couplings and into holes in the inner shell 2. Only one header of each tube-section is shown as thus connected to the water-leg; but both may be similarly connected, if desired. The upper

ends of the headers are connected to the crown-sheet 6 by hollow plugs 14, that strew into holes in the sheet, and communication is thereby established between the tube-sections in the combustion-chamber and the space or chamber above the sheet.

Above the crown-sheet 6 are fire tubes or flues 15, arranged in vertical series and having their lower ends connected to the crown-sheet and their upper ends connected to a circular plate or head 16, whereby communication is established between the combustion-chamber and the interior of the smoke-flue 17. The lower end of the smoke-flue is connected by a tight joint to the plate 16 and the upper end to the head 18 of the shell 1. The space intervening the cylinder 1 and its head and the flue 17 constitutes the steam space or dome. A steam-outlet 19 is placed in communication with this space.

In operation, the water-level being maintained at a point between the crown-sheet and the plate 16, water enters the headers 9 and tubes 10 from the water-leg and as it becomes heated flows, together with whatever steam may have been generated, upward into the water-space above the crown-sheet, where it is subjected to the heat of the crown-sheet and fire-tubes, and the steam generated rises into the steam-dome.

Having described my invention, what I claim, and desire to secure by Letters Patent, is—

1. In a steam-generator, in combination; outer and inner concentric shells providing a water-jacketed fire-box, the inner shell being the shorter and provided with a crown-sheet; a head and a depending funnel-shaped smoke-flue with a closed base covering the outer shell and providing an intermediate steam-space; a series of removable tube-sections arranged in parallel vertical planes, each tube-section comprising a pair of opposite vertical headers and inclined tubes connecting them, the inclinations of the tubes being opposite in adjoining sections; detachable pipe-couplings connecting the lower ends of the headers with the water-leg and detachable plugs connecting their upper ends with the crown-sheet; and a series of vertical flues connecting the crown-sheet and smoke-flue.

base for the passage of the products of combustion from the fire-box to the smoke-flue, substantially as set forth.

2. In a steam-generator, in combination; 5 outer and inner concentric shells providing a water-jacketed fire-box, the inner shell being the shorter and provided with a crown-sheet; a head and a smoke-flue closing the top of the outer shell; a series of removable tube- 10 sections arranged in parallel vertical planes, each tube-section comprising a pair of opposite vertical headers and tubes connecting them; detachable pipe-couplings connecting the lower ends of the headers with the water-

leg and detachable plugs connecting their upper ends with the crown-sheet; and a series of vertical flues connecting the crown-sheet and smoke-flue base for the passage of the products of combustion from the fire-box to the smoke-flue, substantially as set forth. 15

In testimony whereof I have signed my name to this specification, in the presence of two subscribing witnesses, this 17th day of April, 1902.

HERBERT E. PENNEY.
